O. JUNGHANS

MECHANICAL TIME FUSE

Filed June 27, 1925

Fig. 2.

Inventor:

Oskar Junghans
By *Lucas*
Attorney.

UNITED STATES PATENT OFFICE.

OSKAR JUNGHANS, OF SCHRAMBERG, GERMANY.

MECHANICAL TIME FUSE.

Application filed June 27, 1925. Serial No. 40,053.

To all whom it may concern:

Be it known that I, OSKAR JUNGHANS, a citizen of the German Republic, residing at Schramberg, Gaishaldenstrasse 134, Germany, have invented certain new and useful Improvements in Mechanical Time Fuses, of which the following is a specification.

This invention relates to mechanical time fuses, particularly to such fuses of the Junghans type, in which the setting disk is caused to rotate by the going train or clockwork after the projectile is fired, and is set for the desired time of ignition before firing by means of a rotary cap on the fuse, 10 a pin provided in the cap being arranged to engage with a projection on the setting disk and to carry the latter around with it when the fuse cap is rotated. In fuses of this kind it has been found that the sudden acceleration of rotation that takes place immediately after the projectile is fired gives rise to a force of inertia which has the tendency to displace both the setting disk and the fuse cap provided with the setting pin in a direction opposite to the direction in which the said members are rotated when set, and this, of course, causes trouble and inaccuracies in firing.

The object of this invention is to remove these drawbacks and this is accomplished by provided means for locking both the setting disk and the fuse cap against rotation in the direction of the force of inertia that arises when the projectile leaves the gun. The locking means for the setting disk may consist of a plurality of spring detents which engage with the teeth of the ratchet-like periphery of the setting disk, whilst the locking means for the fuse cap consist in 35 clamping or jamming rolls which prevent rotation of the cap in one direction, but allow it to rotate freely in the other direction.

A constructional form of the invention is illustrated in the drawing.

Fig. 1 is a vertical section through the fuse. The going train which contains the core, and the parts associated with the clockwork are shown herein in side elevation.

Fig. 2 is a horizontal section on the line

2—2 of Fig. 1. The core of the fuse with 50 the setting disk and the locking member for the same are shown in plan view, while the locking means for the ignition cap are shown at the right side of this figure in plan view and at the left side partially in section.

The general construction of the fuse is similar to fuses of the Junghans type. The setting disk *a* is mounted in a known manner on the driving shaft of the clockwork so as 60 to be carried round by friction. It can therefore be easily set for time without affecting the clockwork, but when the clockwork starts running after the projectile is fired from a cannon the disk is carried round by said shaft. The disk *a* is also provided in a known manner with a projection *b* which co-operates with a setting pin *d* fixed in the cap *c*. Attached to the fixed core *e* of the fuse which contains the clockwork are a 70 number of spring detents *e'* which are irregularly distributed around the periphery and which engage in the saw-tooth periphery of the setting disk *a* so as to permit the setting disk to rotate in the direction of 75 the arrow shown in Fig. 2 but to lock the disk against rotation in the opposite direction in which the force of inertia acts when the projectile is fired.

To obviate unintentional rotation of the 80 fuse cap *c* recesses *f* are provided in the part of the periphery of the fuse body *g* that receives the cap. These recesses form pockets which, when the cap *c* is in place, taper in the direction opposite to the direction in 85 which the setting disk is set, *i. e.* the direction of the arrow in Fig. 2. In these pockets *f* are placed rolls *h* which are urged towards the wedge-shaped end of the pocket *f* by means of pins *k* and springs *i*, and by 90 their own weight when the fuse is placed in a horizontal position. By this means the cap is free to move easily in the direction of the arrow (Fig. 2), *i. e.* in the direction in which the disk *a* is set, but it is locked 95 against rotation in a clockwise direction, *i. e.* the direction in which the inertia is effective.

The arrangement of the locking member for the fuse cap offers the further advantage that all possibility of setting the fuse for time by turning the cap against the direction of the arrow in Fig. 2 is precluded.

I claim:

1. A mechanical time fuse for projectiles comprising a fuse body; a fuse having a clockwork mounted in said body; a setting disk for said clockwork and having a saw-tooth periphery; a cap for said fuse body and having means thereon for setting said disk; and locking means engageable with said saw teeth of said disk in order to prevent the rotation of the disk in the opposite direction to that in which it is adapted to be set.
2. Mechanical time fuse for projectiles comprising a driving mechanism with a shaft, a setting disk frictionally coupled to said shaft, a cap rotatable on the body of the fuse, a first locking mechanism for locking the setting disk against rotation in the direction in which a rotational force is imparted to it by inertia when the projectile is fired from the gun, and a second locking mechanism for locking the cap against rotation in the said direction, said first locking mechanism comprising a saw-tooth periphery on said disk and spring detents engaging with said periphery and fixed relatively to the disk.
3. Mechanical time fuse for projectiles comprising a driving mechanism with a shaft, a setting disk frictionally coupled to said shaft, a cap rotatable on the body of the fuse, a first locking mechanism for locking the setting disk against rotation in the direction in which a rotational force is imparted to it by inertia when the projectile is fired from the gun, and a second locking mechanism for locking the cap against rotation in the said direction, said second locking mechanism comprising recesses in the body of the fuse bounded by the internal wall of the cap and tapering in the direction of rotation opposite to that in which the disk is turned when it is set, and jamming rolls placed in said recesses.
4. Mechanical time fuse for projectiles comprising a driving mechanism with a shaft, a setting disk frictionally coupled to said shaft, a cap rotatable on the body of the fuse, a first locking mechanism for locking the setting disk against rotation in the direction in which a rotational force is imparted to it by inertia when the projectile is fired from the gun, and a second locking mechanism for locking the cap against rotation in the said direction, said second locking mechanism comprising recesses in the body of the fuse bounded by the internal wall of the cap and tapering in the direction of rotation opposite to that in which it is adapted to be set.

the disk is turned when it is set, jamming rolls placed in said recesses, and means for urging the rolls in the direction of taper of said recesses.

5. Mechanical time fuse for projectiles comprising a driving mechanism with a shaft, a setting disk frictionally coupled to said shaft, a cap rotatable on the body of the fuse, a first locking mechanism for locking the setting disk against rotation in the direction in which a rotational force is imparted to it by inertia when the projectile is fired from the gun, and a second locking mechanism for locking the cap against rotation in the said direction, said second locking mechanism comprising recesses in the body of the fuse bounded by internal wall of the cap and tapering in the direction of rotation opposite to that in which the disk is turned when it is set, jamming rolls placed in said recesses, and springs for urging the rolls in the direction of taper of said recesses.

6. A mechanical time fuse for projectiles comprising a fuse body provided with a clockwork; a setting disk for said clockwork and having a saw-tooth periphery; means for setting said disk; and locking means engageable with said saw-teeth of said disk in order to prevent the rotation of the disk in the opposite direction to that in which it is adapted to be set.

7. A mechanical time fuse for projectiles comprising a fuse body provided with a clockwork; a setting disk for said clockwork and having a saw-tooth periphery; and locking means engageable with said saw-teeth of said disk in order to prevent the rotation of the disk in the opposite direction to that in which it is adapted to be set.

8. A mechanical time fuse for projectiles comprising a fuse body provided with a clockwork; a setting disk for said clockwork and having a saw-tooth periphery; locking means engageable with said saw teeth of said disk in order to prevent the rotation of the disk in the opposite direction to that in which it is adapted to be set; a cap for said fuse body; and means in said fuse body engageable with said cap for preventing rotation of the cap in the direction in which the inertia is effective when the projectile is fired.

9. A mechanical time fuse for projectiles comprising a fuse body; a fuse having a clockwork mounted in said body; a setting disk for said clockwork and having a saw-tooth periphery; a cap for said fuse body and having means thereon for setting said disk; locking means engageable with said saw-teeth of said disk in order to prevent the rotation of the disk in the opposite direction to that in which it is adapted to be set; and means in said fuse body engageable

with said cap for preventing rotation of the cap in the direction in which the inertia is effective when the projectile is fired.

10. A mechanical time fuse for projectiles comprising a fuse body provided with a clockwork; a setting disk for said clockwork and having a saw-tooth periphery; locking means engageable with said saw-teeth of said disk in order to prevent the rotation of the disk in the opposite direction to that

in which it is adapted to be set; a cap for said fuse body; and a plurality of spring-pressed rollers in a recess in said fuse body, said rollers being engageable with said cap for preventing rotation of the cap in the direction in which the inertia is effective when the projectile is fired.

In testimony whereof I affix my signature.

OSKAR JUNGHANS.
